(57) **CLAIM**

The ornamental design for a corner connector as shown and described.

DESCRIPTION

FIG. 1 is a top, front perspective view of a corner connector; FIG. 2 is an enlarged, left-side elevation view thereof; FIG. 3 is an enlarged, right-side elevation view thereof; FIG. 4 is a rear elevation view thereof; FIG. 5 is a bottom plan view thereof; FIG. 6 is a top plan view thereof; FIG. 7 is a front elevation view thereof; and, FIG. 8 is a left-side elevation view thereof, in an installed environment.

All broken lines represent structure or features that form no part of the claimed design. Specifically, the dash broken lines form portions of the corner connector that are unclaimed and/or portions of environmental structure, on which the corner connector is incorporated or installed that form no part of the claimed design.
